G. W. BROOKS,
BLACKBOARD,
APPLICATION FILED MAY 2, 1921.

Patented Nov. 7, 1922.

Inventor
George W. Brooks

By *E. W. Brooks*

Attorney

UNITED STATES PATENT OFFICE.

GEORGE W. BROOKS, OF TOPEKA, KANSAS.

BLACKBOARD.

Application filed May 2, 1921. Serial No. 465,953.

To all whom it may concern:

Be it known that I, GEORGE W. BROOKS, a citizen of the United States, residing at Topeka, in the county of Shawnee and State 5 of Kansas, have invented certain new and useful Improvements in Blackboards, of which the following is a specification.

This invention relates to certain new and useful improvements in blackboards of that 10 class formed of a metallic base or foundation with a writing surface applied thereto.

I am aware that it has been proposed to provide a flexible metallic blackboard having a writing surface applied thereto. In 15 one form of such prior construction the blackboard is composed of a foundation of very thin and flexible sheet steel, the face of which is covered with a heavier material of elastic pigment to overcome the unevenness 20 of the ordinary commercial steel as manufactured.

On account of this steel being very uneven and full of buckles and varying angles, it seems the patentee (Costello, Jan. 23, 25 1906) levels up the surface with the elastic pigment, correcting the unevenness of the surface of the steel by the application of a layer of elastic pigment, and this foundation forms the blackboard.

At the time when said patent was granted—1906—a commercial grade of steel, having a scaly and uneven surface, made by the Bessemer process and rolled into sheets with the flake of scale rolled in, made a very 30 poor quality of sheet steel. This was owing to the poor state of the development of rolling and it was practically impossible at that time to obtain a flat or unwavy sheet. The application of a layer of elastic pigment was 35 to overcome this objection and prepare a surface on the uneven foundations of the sheet steel for blackboard purposes. Great stress was given to the fact that the material used to cover this irregular surface should 40 be properly covered with elastic and strong combination of materials and the patentee describes those suitably adapted to give the proper qualities to spread readily and smoothly to overcome the unevenness or 45 faulty surface of the steel sheet.

Today, there has been perfected a practical level and true steel by a process known as pickling and patent leveling. By using a sheet of metal of this description prepared

in this manner, I have reversed this idea 55 and patent and depend upon the patent leveling surface of the sheet itself to form the true surface of the blackboard.

The coating of abrasive material which I apply does not cover up or smooth out any 60 unevenness or irregularity in the sheet and only a light coating is necessary. It is a fact that I correct the faulty foundation by using patented leveled steel.

I make no claim to a flexible metal foun- 65 dation, my blackboard being rigid and non- flexible, permanently set, and that is obtained by using suitable heavier gauge ma- 70 terial which is non-flexible and not neces- sarily coated by flexible material and not one that can be rolled and, on account of its flexibility, shipped in a rolled form. My blackboard is non-flexible.

By my construction no trouble is occa- 75 sioned by expansion joints, as a perfectly level sheet can be had by butt-welding together a plurality of contiguous sections, and a continuous and level surface of dif- 80 ferent sections can be obtained without the use of elongated holes or a cover plate for concealing the joints of the different sec- tions of blackboard.

I form a blackboard of a non-flexible metal base or foundation made by the pat- 85 ented "level" process, which, of course, is level and true, does not have irregularities or waves and is coated with a suitable abra- 90 sive surface. It does not require a backing of any other material, but can be coated or galvanized or sherardized or any other 95 method may be used, primarily to protect it from rusting, and the true and plain permanent surface may be used for blackboard purposes by suitably coating or covering the working surface.

It can be bent permanently into suitable shape and stiffened by application of angles and reinforcements to make a solid substan- 100 tial blackboard of light weight material.

It can be made to conform to right angles or irregular corners of the building.

It can be made straight, cylindrical or irregular in shape and used as a portable board.

It is not subject to warping and the sun 105 or heat does not crack or destroy it.

This metallic blackboard is coated with a base coat of enamel or analogous prepara-

tion to protect the metal against rusting. On the top of this coat are one or more coats of black or any other color enamel. These coats are baked on the metal and make a 5 permanent finish.

The last or finished coat is formed of suitable proportions of emery flour. This makes a permanent covering which when baked on the metal gives the requisite amount of abrasive surface to cut into the chalk and leave the chalk trace on the board forming the letters intended to be made. 10

This preparation makes a permanent coat and different from slate in several respects.

15 By the process of enameling, an absolutely dark surface is obtained; either with a gloss or dull surface it makes a greater contrast with chalk than the slate color does.

By enameling the surface of metal it has 20 a solid base and is not porous and the chalk does not grind away as quickly when the emery flour mixture is suitably proportioned to the finished coat as it only uses enough chalk at each application to leave 25 a trace of chalk.

Chalk has to be cleaned out of a porous surface, but is erased from a metal board having an enamel surface very easily and leaves the board absolutely clean and free 30 from chalk.

Other objects and advantages of the invention will hereinafter appear and the novel features thereof will be particularly pointed out in the appended claims.

35 The accompanying drawing illustrates an example of my present invention and in which is shown a perspective view of a portion of a blackboard constructed in accordance with the principles of my invention as 40 hereinbefore outlined, parts being removed and other parts shown in section.

In the drawing,

1 designates the base or foundation of the board which is of non-flexible metal, preferably that made by the patented "level" process which is level and true without irregularities or waves, and 2 is an anti-rust preparation constituting the base coating, which may be of enamel or analogous

preparation to protect the metal plate 50 against rusting.

3 designates a coating of black or any other color of enamel, of which there may be one, two or more coats one after each baking. The metallic base thus coated is baked 55 so as to make a permanent finish while the finishing coat 4, of an abrasive nature, such as a suitable mixture of emery flour, when baked on the coated metal, provides a permanent covering and gives the requisite 60 amount of abrasive surface to cut into the chalk and leave the clear plain chalk trace on the board forming the characters intended to be made.

The emery coating may be formed by 65 mixing the requisite proportion of the emery with the coating of enamel.

What is claimed as new is:—

1. A blackboard or the like composed of a sheet steel inflexible base; and a plurality 70 of coats of enamel thereon each independently baked, the last coating being of an abrasive nature and the whole constituting a hard, permanent level writing surface.

2. A blackboard formed of an inflexible 75 metallic base, an anti-rust coating thereon, a coating of enamel on said anti-rust coating, and a finishing coating embodying an abrasive substance, the same forming a hard permanent inflexible writing surface.

3. A blackboard formed of an inflexible metallic base, an anti-rust coating thereon, a coating of enamel on said anti-rust coating, and a finishing coating embodying an 80 abrasive substance all baked to give a permanent finish, the same forming a hard permanent inflexible writing surface.

4. A blackboard or the like composed of a sheet steel inflexible base; an anti-rust enamel coating baked thereon, and a plurality 85 of coats of enamel thereon each independently baked, the last coating being of an abrasive nature and the whole constituting a hard, permanent level inflexible writing surface.

In testimony whereof I affix my signature.

GEORGE W. BROOKS.
